RECOVERY OF JUICES FROM SUGAR MUDS

Jerónimo Diaz-Compañ, Central Senado, Cuba

Application March 21, 1944, Serial No. 527,496
In Cuba April 12, 1943

14 Claims. (Cl. 127—43)

1 This invention relates to recovery of juices from sugar muds; and it comprises a process of treating sugar scums or muds, such as the mud recovered from the usual clarifying units or the filter cake recovered from a continuous filter operating on the clarifier mud; said process comprising applying such a mud to the bagasse blanket passing through a plurality of cane grinding mills at a point between the final mill and the last point at which any maceration water is applied to the blanket, whereby washing away of said mud with maceration water is avoided and the sugar juice contained in the mud is recovered; said process being preferably conducted by forming two separate bagasse blankets from the bagasse passing through the mills, introducing the mud between said blankets and passing the resulting assembly through a final mill to extract juice therefrom; all as more fully hereinafter set forth and as claimed.

In the process of recovering juices from sugar cane the cane is passed through a series of crushing or grinding mills. The crushed cane forms what is known as a bagasse blanket during its passage through the mills and this blanket is thereafter used in the furnaces to produce power for the sugar manufacturing operations. In the sugar processing operations, which are conducted in the "sugar house" or "boiling house," muds or scums are produced. For example the clarifying units (clarifiers) produce a mud known as "cachaza." These muds or scums are conventionally treated for recovery of their sugar values. Usually they are passed to a continuous rotary vacuum filter where fine bagasse, known as bagacil, is used as a filter aid.

Owing to the fact that most sugar cane factories have deficient heat balances, that is, heat balances which require fuel in addition to that supplied by the bagasse, it is frequently necessary to burn the muds or the filter cakes from the conventional continuous filters. The muds represent about 3.2 per cent of the total cane and hence, if sufficiently dehydrated, constitute a valuable source of fuel. But the filter cakes from the usual continuous filters contain from about 75 to 85 per cent of moisture (2 per cent sucrose). In contrast the bagasse blanket from the grinding mills contains only about 50 per cent moisture (3 per cent sucrose). If the muds are added directly to the bagasse blanket before the latter is sent to the furnaces, as is conventional in many sugar factories, the moisture content of the blanket is increased to about 53.5 per cent, which is, of course, a decided disadvantage from a fuel standpoint.

It has heretofore been proposed to add the muds or scums from the sugar house to the bagasse blanket as it is passing through the first mill of the series and prior to the mill or mills

supplied with maceration water. If this procedure was ever employed practically, it has long since been abandoned. In my tests leading up to the present invention I discovered why it is not practical to add the muds to the bagasse blanket prior to the maceration water. If this is done, the top of the bagasse blanket becomes slimy and slippery and the grinding efficiency is substantially reduced. Moreover the maceration water, which is usually hot, tends to dissolve impurities from the muds and to wash them through the bagasse blanket, resulting in juices of considerably lower purity. This increases the clarification difficulties and results in an inferior sugar of low keeping quality.

2 I have discovered that the above difficulties can be avoided by adding the muds at a point between the final mill of the grinding unit and the last point at which any maceration water is added. If the maceration water is added to the blanket prior to the muds, it soaks into the blanket and has time to cool. When the blanket is then passed through the final mill, the maceration water squeezed out does not flush over and wash away the muds or dissolve the impurities therefrom, as it does when it is sprayed on top of the muds. The muds are then dehydrated to a moisture content of about 50 per cent and the moisture removed serves as re-maceration water in the last mill to reduce the sucrose content of the bagasse blanket. A double advantage is thereby gained. Moreover the muds soak into the bagasse blanket and, since they are not contacted directly with maceration water, they do not become slimy and slippery. The grinding efficiency of the grinding unit is not reduced appreciably.

It is possible in my new process to apply the muds directly as they are received from the boiling house or after they have been dehydrated to a certain extent by means of a continuous filter. The filter cake from such a filter can be applied to the bagasse blanket prior to the last mill for example. It is usually advantageous to mix the filter cake with water before applying it to the bagasse blanket. The moisture content of the filter cake, including the mud, is reduced to about 50 per cent, whereby its fuel value is greatly enhanced.

3 If maceration water is applied at the third from the last mill but not at the last or next to the last, the muds can be applied to the bagasse blanket at the intermediate carrier of the next to last mill. The moisture contained in the muds is then pressed out in the last mill and this serves to some extent as maceration water. If maceration water is applied at the next to last mill, the muds can then be applied to the bagasse blanket at a point between the two final mills, thus giving the maceration water a short time to cool and to soak

into the bagasse blanket before the muds are applied thereto.

A more advantageous method of conducting the present invention is to provide a separate mill for grinding the muds. This mill can be of the conventional two or three-roll type. The bagasse blanket coming from the last mill of the usual grinding unit can then be split in sections, one or two sections being directed to the mud grinding mill. The muds can be applied to one section of the blanket, which can then be passed directly through the mill, but preferably a second section of the bagasse blanket is superposed on top of the muds, whereby the muds are compressed between two bagasse blankets as they are passed through the mud grinding mill. In this fashion no liquid can escape from the muds without passing through a bagasse blanket which serves as a highly efficient filtering medium. The reincorporation of impurities obtained in this fashion is very small. The liquid expressed is clear and free from all solid impurities, its purity usually being higher than that of the juices recovered from the usual continuous vacuum filters. The liquid contained in the muds serves as maceration water, resulting in a higher recovery of sucrose, and the muds are dehydrated more efficiently, resulting in a higher fuel value.

It is evident from the above that, when my method is used, the conventional rotary vacuum filter can be dispensed with. But if it is desired to employ such a filter, for example, when a filter is already installed, it is possible to pass the filter cake to the bagasse blanket directly or to mix it with water prior to such passage. Any water mixed with the filter cake serves as maceration water, resulting in an increased recovery of sucrose.

The low-purity juices recovered from the mill which grinds the muds in accordance with my invention are advantageously recycled as re-maceration juices. They can, of course, be treated specially or disposed of in other ways.

My invention can be explained with somewhat greater accuracy by reference to the accompanying drawing in which the several figures constitute flow charts showing three modifications of my process.

In this showing

Fig. 1 is a flow chart showing the muds applied at the intermediate carrier of the next to last mill,

Fig. 2 shows the muds applied to the bagasse blanket between the two final mills, while

Fig. 3 shows my preferred process in which the muds are introduced between two bagasse blankets passing through a mud grinding mill.

The processes illustrated in the flow charts of the drawing are believed to be obvious from a study of these figures. In Fig. 1, for example, the sugar cane is delivered to the first mill at the left side of the figure and the resulting bagasse is passed from mill to mill in the form of a blanket and finally to the furnace (not shown) at the right side of the figure. The juice expressed by the first two mills is conducted to the boiling house, while that from the last two mills is delivered to the first mill for re-maceration. Maceration water is added at the intermediate carrier of the second mill, while mud from the boiling house or from the filters is delivered on top of the bagasse blanket at the intermediate carrier of the next to last mill.

In Fig. 2 the bagasse passes through the mills

water is added at the next to the last mill. The muds are therefore added to the bagasse blanket at a point between the last two mills in order to avoid washing away of the mud and dissolving of impurities by the maceration water. The juice from the last two mills is separated, that from the last mill being delivered for re-maceration to the second mill, while that from the next to last mill is delivered for re-maceration to the first mill.

In Fig. 3 the bagasse passes through the first four mills as before but is divided into two or three sections after leaving the fourth mill. A fifth mud grinding mill is provided, which may be smaller than the other mills. At least one section of the bagasse is passed as a blanket to this mud grinding mill. The mud from the boiling house is passed to the vacuum filter and the resulting filter cake is first mixed with water and then deposited on the bagasse blanket passing to the mud grinding mill. Alternatively the mud may bypass the filter, as indicated by dotted lines in the flow sheet, and be sent directly to the bagasse blanket. Preferably a second section of the bagasse blanket is superposed on top of the mud applied to the first section, so that the mud is enclosed between the two blankets as the assembly is passed through the mill. The juice from the next to last mill is used as re-maceration at the first mill. The bagasse blanket and dehydrated mud from the mud grinding mill is united with the remaining bagasse from the grinding unit and sent to the furnace at the right of the figure.

My tests show that my process, as shown in Figs. 1 and 2, can be applied to the grinding units in which 22 rolls are employed without any detectable reduction in grinding efficiency. In the case of the smaller units, employing up to 17 rolls, a slight reduction in efficiency is obtained but this is so small that the advantages gained outweigh this slight disadvantage. When a separate mud grinding mill is employed the efficiency of the grinding unit is not affected, while the efficiency of the mud grinding mill is high even when only a single bagasse blanket is passed through this mill.

It is evident that the process as described has several important advantages among which are the following:

1. The mud after being treated by my process has substantially the fuel value of the usual bagasse blanket. The total fuel value of the blanket plus mud is sufficient in many cases to produce power in excess of that required in the sugar processing, and this excess power can be employed for other purposes.

2. The fuel value of the mud treated by my process is substantially greater than that of the filter cake, including the mud, which is obtained from the usual vacuum filters.

3. More sucrose is recovered from the boiling house muds than can be recovered with the use of vacuum filters owing to the lower juice content (50 per cent moisture) of the mud processed in accordance with the present invention.

4. Additional sucrose is recovered from the bagasse blanket for the reason that the moisture expressed from the muds serves as maceration water. This is particularly true when the mud is mixed with maceration water before being applied to the bagasse blanket.

5. Sugars and final molasses of better quality are obtained due to superior juice clarification,

since the solids and impurities in the muds adhere to the bagasse blanket.

6. The roll surfaces do not become glossy and slippery because mud solids remain inside the bagasse blanket and are not contacted with the rolls after being washed with maceration water.

7. The usual rotary vacuum filter can be dispensed with, if desired, resulting in a substantial saving, especially in maintenance.

While I have described what I consider to be the most advantageous embodiments of my invention, it is obvious, of course, that many modifications can be made in the specific procedures described without departing from the purview of this invention. The recycling of the expressed juices to be used for re-maceration can be accomplished in several different ways, depending upon how many mills and how many rolls are employed. If a special mud grinding mill is employed, this can be located at any convenient position with respect to the other mill units. Conventional means can be used for removing bagasse from the bagasse blanket coming from the grinding mill unit, in order to form the blanket or blankets to be used in the mud grinding mill. And it is possible to deposit the mud or filter cake on one bagasse blanket followed by enclosing this assembly between two additional bagasse blankets. The bagasse blankets passing to the mud grinding mill may be of the order of 4 inches thick while the layer of mud may have a thickness of approximately $\frac{3}{8}$ inch. Other modifications of my invention which fall within the scope of the following claims will be immediately evident to those skilled in the art.

What I claim is:

1. In the process of recovering juices from sugar muds, wherein sugar cane is passed through a series of cane grinding mills in the form of a bagasse blanket, the step which comprises depositing a sugar mud on said bagasse blanket before the blanket passes through the last mill of said series but subsequent to the application of any maceration water to said blanket.

2. The process of claim 1 wherein said mud is applied on said bagasse blanket at the intermediate carrier of a mill receiving no maceration water, said blanket being then passed through the final mill.

3. The process of claim 1 wherein maceration water is added to the next to last mill of the series while the mud is applied to said bagasse blanket at a point between the last two mills.

4. The process of claim 1 wherein said mud is the filter cake from a filter operating on a sugar mud and wherein said filter cake is mixed with maceration water prior to deposition on said bagasse blanket.

5. In the process of recovering juices from sugar muds, wherein sugar cane is passed through a series of cane grinding mills in a grinding unit, the cane being formed into a bagasse blanket during said passage, the improvement which comprises dividing the bagasse blanket from said grinding unit into at least two sections, passing one of said sections in the form of a bagasse blanket through a mud grinding mill and depositing a sugar mud on said last mentioned bagasse blanket before it passes through said mud grinding mill and subsequent to the application of any maceration water to the blanket.

6. The process of claim 5 wherein said sugar mud is cachaza derived from a boiling house clarifier.

7. The process of claim 5 wherein said sugar mud is a filter cake from a filter operating on a boiling house sugar mud.

8. The process of claim 5 wherein said sugar mud is a filter cake from a filter operating on a boiling house sugar mud and wherein said filter cake is mixed with maceration water prior to deposition on said bagasse blanket.

9. In the process of recovering juices from sugar muds, wherein sugar cane is passed through a series of cane grinding mills in a grinding unit, the cane being formed into a bagasse blanket during said passage, the improvement which comprises dividing said bagasse blanket into at least two sections, depositing a sugar mud on top of one of said sections, applying a second section on top of said mud, and then passing the resulting assembly through a mud grinding mill to express the juices and any added water from said mud.

10. The process of claim 9 wherein said sugar mud is cachaza derived from a boiling house clarifier.

11. The process of claim 9 wherein said sugar mud is a filter cake from a filter operating on a boiling house sugar mud.

12. The process of claim 9 wherein said sugar mud is a filter cake from a filter operating on a boiling house sugar mud and wherein said filter cake is mixed with maceration water prior to passage through said mud grinding mill.

13. The process of claim 9 wherein juices recovered from said mud grinding mill are used for re-maceration, being passed to a mill in front of a mill receiving maceration water.

14. In the process of recovering juices from sugar muds, wherein sugar cane is passed through a series of cane grinding mills in a grinding unit, the cane being formed into a bagasse blanket during said passage, the improvement which comprises dividing the bagasse blanket from said grinding unit into at least two sections, passing one of said sections in the form of a bagasse blanket through a mud grinding mill, depositing a sugar mud on said last mentioned bagasse blanket before it passes through said mud grinding mill and subsequent to the application of any maceration water to the blanket, and recycling the low-purity juice recovered from said mud grinding mill as re-maceration juice to a mill in front of said mud grinding mill.
